SWIVEL CONNECTION FOR VACUUM
CLEANER NOZZLES

Edward Carl Bank, Berkeley, Calif.

Application February 9, 1935, Serial No. 5,713

3 Claims. (Cl. 285—212)

This invention relates to vacuum cleaner nozzles and particularly to a device for mounting a vacuum cleaner nozzle for universal movement with respect to the vacuum tube to which it is attached.

It is common practice in vacuum cleaners to employ a nozzle that is rigidly attached to the vacuum tube and extends transversely thereof. While this construction is suitable for cleaning ordinary floor space, it presents many disadvantages in connection with cleaning beneath furniture and in small or narrow spaces such as frequently exist between a heavy piece of furniture and the wall. When it is desired to clean walls, moldings, drapes and bric-a-brac of one kind or another, it is often found that the rigidly connected nozzle is inconvenient to manipulate to the best advantage.

It is the object of the present invention to provide means for connecting a nozzle to a vacuum tube that will permit relative movement between the nozzle and the tube to an extent that will facilitate adapting the nozzle to as many household uses as possible and to provide a connection of simple and inexpensive form that will increase the efficiency of and expedite the cleaning operation.

One form of my invention is exemplified in the accompanying drawings and described in greater detail in the following specification in which further of its objects and advantages are made apparent.

In the drawings—

Fig. 1 is a central vertical section through a nozzle of conventional type connected to a vacuum tube by a joint embodying one part of my invention;

Fig. 2 is a section taken on the line II—II of Fig. 1;

Fig. 3 is a section taken on the line III—III of Fig. 1;

Fig. 4 is a front elevation of the device illustrated in Fig. 1;

Fig. 5 is a central vertical section through a brush type nozzle connected to a vacuum tube by means similar to those illustrated in Fig. 1, and also provided with means for permitting rotation of the brush in a horizontal plane;

Fig. 6 is a front elevation of the device shown in Fig. 5; and

Fig. 7 is a section taken on the line VII—VII of Fig. 5.

Referring more particularly to the drawings, a vacuum cleaner nozzle is generally indicated at 10 in Figs. 1 and 4. The nozzle 10 is connected to a vacuum tube 11 which extends upwardly at an angle therefrom to serve as a handle by means of which the nozzle 10 is moved over the surface to be cleaned. Ordinarily the angle between the nozzle and the tube 11 is fixed so

that there is some difficulty in maintaining the mouth of the nozzle flat against the floor; this position being required to obtain the maximum amount of suction on the surface directly beneath the nozzle. With this angle fixed, it is difficult, and particularly so for persons of greater or less than average height, to maintain the nozzle at the proper angle and, furthermore, when it is desired to clean beneath a chair, bed or other article of furniture, it being necessary to lower the tube 11, the open end of the nozzle is placed at an angle to the floor and it is impossible to obtain maximum efficiency.

My invention provides for free movement of the handle or tube 11 in a vertical plane with respect to the nozzle 10 so that regardless of the angle between these members, the nozzle will always operate with the highest degree of efficiency.

In the embodiment of my invention shown in the drawings, this is accomplished by means of an upwardly extending elbow 12 connected to the nozzle and a downwardly extending elbow 13 connected to the tube 11. The elbows 12 and 13 are of the same radius and the former telescopes within the latter. The centers of the radii of the elbows 12 and 13 are concentric so that the elbows may be connected for pivotal telescoping movement by a pin 14 extending through spaced ears 15 on the elbow 13 and an ear 16 on the nozzle 10.

With this construction, it is possible for the tube 11 to be moved from an uppermost position, such as illustrated in Fig. 1, to a lower position, such as illustrated by dotted lines in the same figure, at which position it is substantially horizontal to the floor with the nozzle 10 meanwhile remaining in a position relative to the floor that will permit a maximum cleaning efficiency.

I have also provided means for frictionally resisting this swinging movement of the handle with relation to the nozzle as well as means for locking the parts in any desired position of adjustment, and means for limiting the angle of adjustment to any desired arc.

The means above referred to are as follows: A flat bar 17, curved on an arc struck from the same center as the radii of the elbows 12 and 13, is secured by a screw 18 to the nozzle 10. This bar overlies the elbows and is received between guides 19 formed on the forward face of the elbow 13 for sliding movement relative to the elbow. A plate 20 bridges the guides 19 and overlies the bar 17 as best illustrated in Fig. 2. A thumbscrew 21 threadedly mounted in the plate 20 may be tightened to provide any desired degree of frictional resistance to the telescoping movement of the elbows 12 and 13; it being understood that the thumbscrew is fixed

relative to the outer elbow 13 while the bar 17 is fixed at its lower end relative to the inner elbow 12. A thin hardened steel plate 22 may be provided beneath the bar 17 and a hardened steel shoe 23 may be arranged at the inner end 5 of the thumbscrew 21 to promote smooth action as the parts slide relative to each other and to prevent undue wear of the other parts which are customarily formed of brass, aluminum or 10 other similar relatively soft metal.

The object of the set screw 21 is first to provide sufficient friction to overcome the tendency of the nozzle to swing freely with relation to the tubular handle 11 and to maintain it in 15 any position of adjustment under ordinary working conditions. The set screw may also be manipulated by further tightening movement to rigidly clamp the parts in any desired position of adjustment.

Under certain conditions it may be desirable 20 that the swinging movement between the nozzle and handle be limited and for this purpose I have provided a member, preferably in the form 25 of a wire 24, connected at one end by a screw 25 to the elbow 13 and at the other end to the plate 20, which is also fixed relative to the elbow 13. This wire is curved parallel to the outer 30 surface of the elbow and extends through a hole 26 in an upturned end 27 on the bar 17. A stop 28 is slidable on the wire 24 but adapted to 35 be locked in any desired fixed position thereon by means of a thumbscrew 29. Thus, when the tubular handle 11 is swung downwardly, the stop 28 will abut against the upturned end 27 of the bar 17 and definitely limit the downward 40 swinging movement of the handle.

Referring now to Figs. 5, 6 and 7 of the drawings, I show the device described above connected with a nozzle 30 of the brush type which 45 comprises a hollow body member 31 having an opening formed centrally therethrough and having a marginal row of bristles 33. In these figures of the drawings, the connection described above is supplemented by a connection which 50 provides for rotational movement of the nozzle independently of raising and lowering movement of the handle. This rotational movement is made possible by a circular plate 34 secured to the top surface of the brush nozzle in a position 55 surrounding the central opening thereof, and provided with upwardly extending peripheral flanges as shown at 35 in Figs. 6 and 7. The flanges 35 are shown as discontinued at the forward and rearward edges of the brush so as not to overlie the same to present sharp edges 60 that would mar furniture or other objects against which the brush may strike.

The lower end of the inner elbow 12 is also 65 provided with a marginal flange 36 which is received between the flanges 35 and thereby guided for pivotal or rotational movement relative to the brush. Clips 37, as best illustrated in Fig. 7, are secured by screws 38 to the flanges 35 and overlie the flange 36 to maintain it in position 70 between the flanges 35. One or more of the clips 37 may be formed of resilient material to bear downwardly upon the flange 36 and thereby afford sufficient frictional resistance thereon to prevent of too free swinging movement of the brush. This frictional resistance may, if desired, be provided by an annular spring washer 75 39, as illustrated in Fig. 6, interposed between the clips 37 and the flange 36.

This swivel connection between the nozzle and the handle permits the nozzle to be rotated with respect to the handle to facilitate access to narrow recesses that must be cleaned and to expedite the cleaning of objects of various shapes and in various positions that may be more easily reached with the brush or nozzle positioned in this manner.

With the combination of the means disclosed for providing swinging movement of the handle relative to the nozzle and rotational movement of the nozzle relative to the handle, it is possible to place the nozzle in any desired position, and with the particular construction of the joints shown, there will be a minimum loss of vacuum, and the means described above for frictionally resisting the adjustment of the nozzle and handle safeguard against the nozzle being loose or dangling at the end of the handle so that it will be firmly held in any desired position of adjustment and at the same time sufficiently free to be moved with little effort to any other desired position.

While I have shown a preferred form of my invention, it should be understood that various changes may be resorted to in the construction and arrangement of its several parts without departing from its scope as defined in the appended claims.

Having thus described my invention, what I claim and desire to secure by Letters Patent is:

1. In a vacuum cleaning device including a vacuum tube and a nozzle therefor, a connection between said tube and nozzle comprising an elbow fixed to the nozzle, an elbow fixed to the tube and telescoping over the elbow on the nozzle, a pivotal connection between the tube and nozzle arranged concentrically with the center of curvature of said elbows, an arcuate bar fixed to the nozzle and lying adjacent the elbows, a thumbscrew fixed with relation to the tube and engageable with said bar to frictionally resist movement of said tube and elbow about said pivotal connection, and an adjustable stop member to regulate the extent of such movement.

2. In a vacuum cleaning device comprising a nozzle and a tubular handle therefor, an elbow formed at the end of said handle, a second elbow telescoping within the first elbow and pivoted thereto for swinging telescoping movement, an annular flange at the outer end of the second elbow, an annular track carried by the nozzle and receiving said flange to permit the second elbow to 50 swivel relative to the nozzle, and resilient means interposed between the flange and said track to resist the swivel action.

3. In a vacuum cleaning device comprising a nozzle and a tubular handle therefor, an elbow formed at the end of said handle, a second elbow telescoping within the first elbow and pivoted thereto for swinging telescoping movement, adjustable means to limit the arc of free swinging movement between the elbows, an annular flange at the outer end of the second elbow, an annular track carried by the nozzle and receiving said flange to permit the second elbow to 60 swivel relative to the nozzle, and resilient means interposed between the flange and said track to resist the swivel action.

EDWARD CARL BANK.
